ESCUTCHEON PLATE

La Verne E. Clayton, Rockford, Ill., assignor to Amerock Corporation, Rockford, Ill., a corporation of Illinois

Filed Apr. 4, 1960, Ser. No. 60,004

Term of patent 14 years

(Cl. D50—6)

FIG. 1 is a front elevational view of an escutcheon plate showing my new design.

FIG. 2 is a perspective view of the escutcheon plate.

FIG. 3 is an enlarged sectional view taken along the line 3—3 in FIG. 1.

FIG. 4 is an enlarged fragmentary front view taken along the line 4—4 in FIG. 3.

FIG. 5 is a fragmentary sectional view taken along the line 5—5 in FIG. 4.

The design for the escutcheon plate disclosed is particularly characterized by the small indentations which are formed on the face in a regular and repeating pattern and which provide a surface texture contrasting with the rest of the plate surface.

I claim:

The ornamental design for an escutcheon plate, substantially as shown and described.
